Primary Examiner — Leanne Was-Englehart*Assistant Examiner* — Alison Davis(74) *Attorney, Agent, or Firm* — Zagorin Cave LLP;
Robert W. Holland(57) **CLAIM**

The ornamental design for an information handling system as shown and described.

DESCRIPTION

FIG. 1 is a front perspective view of the information handling system comprising the present invention;
FIG. 2 is a front elevation view thereof;
FIG. 3 is a rear elevation view thereof;
FIG. 4 is a right side view thereof;
FIG. 5 is a left side view thereof;
FIG. 6 is a top view thereof;
FIG. 7 is a bottom view thereof;
FIG. 8 is a bottom perspective view thereof;
FIG. 9 is a front perspective view of the information handling system in an open position;
FIG. 10 is a detailed view of the information handling system as identified in FIG. 8; and
FIG. 11 is a detailed view of the information handling system as identified in FIG. 10; and,
FIG. 12 is a detailed view of the information handling system as identified in FIG. 8.
The broken lines depict portions of the information handling system that form no part of the claimed design.

1 Claim, 10 Drawing Sheets
